UNITED STATES PATENT OFFICE

151,945

DESIGN FOR A JAR

Frasier Smith, Wheeling, W. Va., assignor to
Jewett & Sherman Co., Inc., Milwaukee, Wis.,
a corporation of Wisconsin

Application July 2, 1947, Serial No. 140,061

Term of patent 14 years

(Cl. D58—25)

To all whom it may concern:

Be it known that I, Frasier Smith, a citizen of the United States, residing at Wheeling, in the county of Ohio, and State of West Virginia, have invented a new, original, and ornamental Design for a Jar, of which the following is a specification, reference being had to the accompanying drawing, forming part thereof.

Figure 1 is a top plan view of a jar, showing my new design;

Figure 2 is a bottom plan view;

Figure 3 is a front perspective;

Figure 4 is a rear perspective; and

Figure 5 is a side elevational view thereof.

I claim:

The ornamental design for a jar, as shown.

FRASIER SMITH.
